ELECTRICAL STORAGE OF INTELLIGENCE

Esmond Philip Goodwin Wright, Joseph Rice, and John David Reynolds, London, England, assignors to International Standard Electric Corporation, New York, N.Y.

Application June 1, 1954, Serial No. 433,741

Claims priority, application Great Britain June 10, 1953

7 Claims. (Cl. 178—2)

This invention relates to electrical systems for the storage of intelligence, with particular, though not exclusive reference, to the storage of constant total permutation code characters.

According to the invention there is provided equipment for the storage of intelligence which comprises a plurality of stores, means for receiving intelligence in, and/or transmitting intelligence from, said stores, means for applying a distributor mark to a store as being the next to be used for reception or transmission, means for transferring such mark from store to store, means for detecting such mark, and means for directing information into or from a marked store under control of said detecting means.

In telegraph switching systems, and in certain industrial telecommunication systems, the necessity arises for storing teleprinter messages for periods of time, which may be long or short, and for retransmitting the messages with or without modifications, and with or without a rearrangement of order.

Systems for effecting this are well known and comprise such devices as paper tape in which signals representing incoming messages may be punched and magnetic tape in which the incoming signals may be stored by magnetic changes in the magnetic material of the tape.

A wide variety of storage devices is now coming into use in which intelligence can be recorded by creating internal strains in the material of the store, and in which stored intelligence or predetermined portions thereof can be detected by detecting the state of strain in the material or in corresponding portions thereof.

The invention is to be described with reference to a particular embodiment in which the form of temporary storage used is a magnetic drum or disc such as has been used in electrical brains as a storage device. Such a magnetic drum consists, for example, of a hollow brass drum having a magnetic skin on its cylindrical surface. This skin provides a number of closely spaced peripheral tracks, with each of which there is associated a recording head and a reading head. Each track provides a number of separate stores and the drum is mounted on a spindle rotatable at high speed by an electric motor.

Intelligence is recorded in the form of successive unspaced longitudinal magnetisations of either one of two kinds, which can conveniently be designated 0 or zero, and 1 or one. Hence it will be seen that intelligence is conveniently recorded in binary digital code, though other code forms are possible. When a recording is to be altered this is done by recording on top of the former recording, i.e. by the magnetic recording technique known as "overprinting."

Each track is divided into a number of separated lengths of track by magnetic markings or the like which leave no physical indication of the division on the actual track. The recording and reading heads are spaced from one another, so that the recorded intelligence is read off, and recorded in a different position, this being effected with such modification of the recording as is necessary. Systems of this type are described in our co-pending applications, Serial Nos. 289,383, 289,385 and 289,386, all filed May 22, 1952.

2

Additional to the tracks on which intelligence is stored there is a track having a recording per element position of all storage tracks. Associated with this track, known as the elements or "clock" track, there is a reading head known as the "clock" head from which there is derived a pulse per element position. By means of delay circuits, this clock pulse cycle is used to derive a set of three time-spaced, narrow pulses per element pulse. These are known as the t_1 , t_2 , t_3 pulses. A further additional track has a recording at the first element position of each storage section. This track is known as the "marker" track and has a "marker" reading head associated with it. This gives a pulse cycle which defines the commencement of each of the storage sections. These 15 two pulse cycles, the clock pulse cycle and the marker pulse cycle, are used to control all operations. Individual applications may require special pulse cycles which can, in general, be derived from these two.

The invention will be described with reference to the 20 accompanying drawing illustrating the embodiment referred to. In the drawing:

Fig. 1 is a diagram to show the allocation of the elements used for making the recording and the relative positions of the pulses and waveforms used during the 25 circuit operation.

Fig. 2 shows the time scale arrangement associated with the reception and retransmission of telegraph signals.

Fig. 3 shows the register used for the temporary 30 storage of received characters and characters to be retransmitted from the store.

Fig. 4 shows the control arrangement for making the recording and also for reading out at a later stage.

Fig. 5 shows the unit used for making the necessary 35 recording.

Fig. 6 shows the unit used to retransmit characters as read from the memory into the register.

Fig. 7 shows illustrative waveforms for the reception of a three character message.

Figs. 8(i) and (ii) show illustrative waveforms for the transmission of the message received as in Fig. 7, and

Fig. 9 is a block diagram which indicates the association of the circuits of Figs. 2 through 6.

In Fig. 1, (a) shows the section of the drum associated with a particular recording. This section is divided into a number of elements, the first of which, T, is used in connection with the retransmission of a stored message. The element T is "0" when a message is being received but is caused to become "1" when it is desired to retransmit the stored characters. Elements M1, M2, M3, etc. provide a distributor operation for both the reception and retransmission of the message. In the initial state M1 is a "1" and M2, M3, etc. are "0." With M1 in the "1" state, the first received character is stored in the five elements following M1 and, as the character is stored, M1 becomes "0" and M2 becomes "1" so that the second received character will be stored in the five elements following M2. This action proceeds until eventually M1, M2, M3, etc. will all be "0" showing that the message is fully received. When element T is made "1" to show that retransmission can commence, the first character passes from the drum store and at the same time M1 is made "1." Similarly as the other characters are read out from the drum the respective Mn are made "1" so that, when the complete message has been retransmitted, M1, M2, M3, etc. will all be "1." Element T is then returned to "0," and, in consequence, M2, M3, etc. become "0" but M1 remains "1" and the record will be back to the initial condition.

The above convention regarding the use of "1" and "0" could, of course, be reversed without affecting the essential functioning of the equipment (only its detailed

arrangement). A similar remark applies to the convention used in this specification of "1" for a "space" telegraph element and "0" for a "mark" element.

The elements 1-5 are associated with the 5 variable elements of a telegraph signal in standard 5-unit constant total permutation code, the first variable element being stored in 1, the second in 2, etc. It should be noted that there is no necessity to provide storage for the start and stop elements as these can be added at the time of retransmission, as will be described.

The waveforms and pulses used in the circuit operation are as follows:

PT is a pulse which becomes positive for the duration of element T.

PL is a pulse which becomes positive for the duration of the last element of a recording section.

PM is a pulse which becomes positive for each of the M_n elements.

WM is a waveform which becomes positive for the sections of the drum which are used to store the telegraph elements. It can be seen that WM is positive when both PT and PM are zero.

t_1 , t_2 and t_3 are the pulses previously mentioned, which occur for each element, t_1 coinciding with the beginning of an element and t_2 and t_3 being progressively delayed.

Not shown in Fig. 1 but used in the circuit arrangement, are $-p$ pulses. These pulses are intended to occur at a rate of 1 in 2 msecs., i.e. 500 cycles/sec. In the description to follow it will be assumed that the rotation time of the magnetic drum is 20 msecs., the time of a unit-period of standard teleprinter code. Thus, by having a clock track arranged to give 10 pulses in each revolution, the necessary $-p$ pulses may be provided. As will be seen, a time scale operating on a ratchet start principle utilises these pulses. If it is considered that the starting error using 500 cycles/sec. as the basic frequency is too great, the rate of these pulses could be increased accordingly by suitably modifying the clock track and adding further dividing stages in the time scale.

Before passing on to a detailed description of the circuit, some explanation of the circuit conventions used is desirable, together with some description of the usage of the component parts of the circuit. A similar form of circuit conventions may be found in U.S. Patent No. 2,653,996.

The circuits are shown throughout in functional form, a convenient arrangement for description since the basic electronic elements used are well-known, few in number and comparatively simple in operation, and readily joined together to give a composite circuit arrangement.

Electronic coincidence gates, well-known per se, are shown as circles with incoming controls shown as radial leads with arrow-heads touching the circle. The output is shown with a radial lead with the arrow-head pointing radially outwards. The number inside the circle indicates the total number of controls which must be energized for the gate to deliver an output; for instance, if there are four controls, and the number in the circle is 2, then the gate will deliver an output when any two of its controls are energised. Gates are indicated by the letter G followed by a reference letter.

A counter comprising a number of single-component stages each of which is capable of assuming one of two conditions, on or off, is shown as a series of rectangles drawn in linear array, e.g. C1 or C2, Fig. 2. The counters shown all count to the end of their cycle and then reset during ordinary operation. Indication is by the letter C followed by a reference number and individual elements of the counter by a further reference figure preceded by a decimal. Individual outputs used as controls are given a lower case c.

A flip-flop, or register, of the bi-stable type has two elements, or positions, and stands always in one or other position, change from one to the other being effected by

a suitable control applied to the non-energised position, and is indicated similarly by the letter F and a reference number; individual outputs being designated by a lower case f.

5 A pattern movement register is shown as a horizontal row of separated rectangles linked together, with an input or controlling gate at the left, outlets being shown from any one or more of the separate elements. Inputs to individual elements may also be indicated by arrows. The 10 usual indication is by means of an R and a reference number, with a decimal number for the individual sections, and a lower case r for the individual outputs as controls. A small circle at one corner of the right-hand element denotes that the register is non-recycling.

15 The phase inverter, shown as X1 in Fig. 3, is used to give a positive output where none exists, and vice versa, and is described and claimed in U.S. Patent No. 2,688,695. This device is useful when a positive output from an element is required, whatever its state, as in R1, Fig. 3. Thus $r1 \cdot 5 \cdot 1$ is a normally positive control, but $r1 \cdot 5 \cdot 0$ is normally zero, i.e. ineffective. By interposing the inverter, however, it becomes a positive control for zero, but zero for the normal output ($r1 \cdot 5 \cdot 1$).

20 Referring first to the layout diagram of Fig. 9, a track on a magnetic drum is divided into a plurality of sections for the storage of items of intelligence. Adjacent the track there are located a recording head and a reading head, the former being associated with a recording circuit (Fig. 5) and the latter with a control circuit (Fig. 4). 25 In Fig. 9, the rectangles bear an indication of the pertinent figure showing the respective detailed circuit, and also of the reference or references used in such detailed circuit figure to indicate the primary control component or components, that is, the time scale, shift register, and flip-flops.

30 35 In the recording operation, items of intelligence, such as character code signals from a teleprinter T/P, are received over an incoming channel, and under the control of the time scale circuit (Fig. 2) are recorded successively in the shift register (Fig. 3), from which under the control of the control circuit (Fig. 4) and recording circuit (Fig. 5) they are recorded on successive sections of the drum track.

40 45 When the storage of a message is completed, the character codes are successively read off the drum track by the reading head and under the control of the control circuit (Fig. 4) and time scale circuit (Fig. 2) are successively recorded in the shift register (Fig. 3). The shift register (Fig. 3), in conjunction with the retransmitting circuit (Fig. 6) and time scale circuit (Fig. 2) controls the energization of a transmitting relay TR which, by the actuation of its contacts, sends appropriate mark and space signals to the outgoing line.

50 55 To pass now to the description of the usage of the component parts of the circuit, the time scale of Fig. 2 will first be described.

It is assumed that recording and retransmission do not occur simultaneously so making it possible to use a common time scale, and also a common register, for each telegraph terminal.

60 65 The time scale consists of two stages, C1 and C2, C1 stepping, when operated, at a rate of 1 step for each $-p$ pulse applied through gate g2, i.e. 1 step in 2 msecs., and C2 stepping once for each complete rotation of C1, i.e. 1 step in 20 msecs. C2 is shown as a 10-position counter although the circuit arrangement makes use of 8 positions only; this is simply due to the fact that a 10-position multi-cathode tube would provide a suitable practical realisation. Any other arrangement using individual gas tubes would be suitable.

70 75 The outputs of C2 are associated with a teleprinter character as follows:

C2.1—start element.

C2.2-C2.6—five variable elements.

C2.7-C2.8—stop elements.

As will be seen later, the time scale is returned to its rest position either before $7\frac{1}{2}$ uniperiods have elapsed from the commencement of the start element during reception or at $7\frac{1}{2}$ uniperiods during retransmission, the latter time being in agreement with normal teleprinter practice in which $7\frac{1}{2}$ unit transmission is used.

The time scale is controlled by means of two start-stop pairs, F1 and F2, F1 being used for receiving a message from a teleprinter and F2 when a stored message is being transmitted.

KRO, the read-off key, is associated with the teleprinter position. KRO is in its normal position whilst the operator is sending a message to store and is operated when the operator has completed the message and wants retransmission to take place. At the end of retransmission the operator restores the key and conditions become as for the initial state.

As stated above, since recording and retransmission do not occur simultaneously, it is possible to use a common register, R1, shown in Fig. 3. However, by the use of two time scales and two registers the system could be modified for simultaneous operation.

The register is a pattern movement register of the type described in U.S. Patent No. 2,649,502. Gates G9—G13 are used for inserting information into the register when signals are being received from the teleprinter (or incoming line). When the five variable elements of a character have been stored, the pattern set up in R1 is stepped by means of G14 and G15, and the output of R1.5 is applied to a drum store for each step. To provide positive information for both a "1" or a "0" stored in R1.5, an inverter, X1, is incorporated so that for a "1," R1.5.1 is positive and R1.5.0 is zero and for a "0," R1.5.1 is zero and R1.5.0 is positive. This has been referred to previously. For convenience, it has been assumed that for a space variable element R1.5.1 will be positive and for a mark variable element R1.5.0 will be positive.

G16 and G17 are used respectively during retransmission for passing information to the register from the memory store and for stepping the pattern after each element has been received. So that the same number of stepping pulses as information elements can be used, instead of having to provide one less by more complicated arrangements, a register R1 having 6 positions namely 0 . . . 5 has been adopted.

Passing now to the control circuit of Fig. 4, F3 is the bi-stable pair used for staticising, element by element, information taken from the drum by the reading device. The arrangement is such that F3.1 is energised for a "1" read from the memory and F3.2 is energised for a "0."

F4 is the bi-stable pair which is used to note that information is to be passed to the memory, F4.1 energised denoting that information may be passed. In the initial state F4.2 is energised but when the time scale passes to the stop uniperiods, during reception of a character, G18 opens causing F4.1 to be energised. G19 is used to return to the state with F4.2 energised.

F5 is the bi-stable pair which allows information stored in the register, R1, to pass to the appropriate character storage section of the memory store. This is accomplished by energising F5.1 via G20, when the correct distributor element, Mn, is encountered. G21 and G22 are used to reset to F5.2 energised when the end of the appropriate section is reached.

F6 is the bi-stable pair which is used to note when information has to be passed from the memory to the register, and is analogous to F4 used for reception. F6.1 is energised via G23 when transfer has to take place and F6.2 is re-energised by either G24, G26 or G27 according to the circumstances.

F7 is the bi-stable pair which allows information to pass from the memory to the register. F7.1 is energised via G28 when the correct distributor element, Mn, is encountered, and is analogous to F5.1 used for reception.

G29 and G30 are used to re-energise F7.2 when the appropriate elements have passed to the register.

F8 is the bi-stable pair which notes that the read-off key, KRO, has been restored to its normal condition. Thus F8 is instrumental in returning the store to its initial state in readiness for receiving further messages.

In the recording unit of Fig. 5, F9 is the bi-stable pair the output of which is associated with the recording device to permit the wanted recording to take place.

G32 and G33 are used in connection with element T of the recording section (vide Fig. 1).

G34—G39 are used in connection with elements M1, M2, M3, etc., the multiplicity of gates being necessary to provide the distributor requirements, previously described.

G40—G43 are used in connection with the recording of the variable elements of the telegraph characters, G40 and G41 being used to recopy a character as read by F3 (Fig. 4), and G42 and G43 being used to insert a new character.

The outputs of F9 are such that when a space telegraph element is to be recorded, F9.1 is energised to record a "1" and when a mark telegraph element is to be recorded, F9.2 is energised to record a "0."

In the retransmission circuit, Fig. 6, F10 is the bi-stable pair used to control a relay TR, which in its turn controls the retransmission of characters read from the drum into the register R1. The controlling gates G46 . . . G53 are associated with time scale positions as indicated by the c inputs applied thereto so that a start element may be added before the five variable elements and a stop element added at the end. $7\frac{1}{2}$ unit transmission is provided. The beginning of each uniperiod is determined by output from C1.2 which is applied to G46 and G49. A control from f2.1 is added in the case of G46 so that F10 does not move to the space side during reception—no such control is needed on the mark side.

With this introduction, it is possible to pass to the detailed description.

The detailed description of the circuit operation will be given in conjunction with Figs. 7 and 8, which illustrate the essential changes for each stage of the reception and retransmission. For illustrative purposes, a message of 3 characters only has been used, the five variable elements of these characters being assumed to be:

- (1) Space Mark Space Mark Space (SMSMS)
- (2) Mark Space Mark Space Mark (MSMSM)
- (3) Space Space Mark Space Space (SSMSS)

In the initial state the following are in the energised condition:

F1.2, F2.2, C1.1, C2.1, F4.2, F6.2, F7.2, F8.2 and F10.2. No section of R1 is energised.

The condition of F3 is dependent upon the condition of the record already on the drum, that is, M1 is a "1," T, M2, M3, etc., are "0" and the character storage sections will be in the condition left from the previous recording. How this state is brought about will be understood from the condition reached at the end of the circuit operation to be described. Fig. 7(a) illustrates the initial condition of the track section.

The condition of F9 is dependent upon the condition of F3, for, in the initial state, G34, G35, G40, G41, G44 and G45 are the only gates (with the exception of G33) which may open and it can be seen that F9 will be set at time t_2 according to the setting of F3 at that time.

When the operator sends the start signal preceding the first character, the send line SL (Fig. 2) changes to space and in so doing energises f1.1. G1 is opened and the next $-p$ pulse to arrive will open G2 and C1 will step under control of the $-p$ pulses. When C1 reaches c1.0, G3 is prepared and the next pulse steps not only C1 but also C2 which moves to position c2.2. When C1 reaches c1.5 with C2 at c2.2, i.e. 30 msecs. from the beginning

of the start element, a time coincident with the centre of the first variable element, the condition of the send line is examined by G9 (Fig. 3). This element is assumed to be space and so G9 will open and $r1.5$ will be energised, and a positive condition will appear at $r1.5.1$.

At a time given by $c1.5$, $c2.3$, i.e. 50 msec. from the beginning of the start element, the line is again examined, this time by G10. Since the second variable element is assumed to be mark, G10 will remain closed and $r1.4$ will remain non-energised. The time scale C1, C2 continues to step and subsequent elements are examined by G11, G12 and G13 in turn. With the assumed first character (SMSMS), the register R1 will be set with $r1.5$, $r1.3$ and $r1.1$ energised, $r1.4$ and $r1.2$ non-energised.

After 120 msec. from the beginning of the start element, C2 will step to $c2.7$. Since C2 will remain in this position for 20 msec. and the drum will make one revolution in this time, there will be one PT pulse (Fig. 1) which will appear during this interval. (Slight variations of the rotational speed will also change the rate of the $-p$ pulses which step C1 and C2 and so there will always be a coincidence between $c2.7$ and PT). Thus G18 (Fig. 4) will open and $f4.1$ will be energised. The operation of $f4.1$ energises $f1.2$ (Fig. 2) closing gate G1 and the time scale C1, C2 is stopped. The changeover of F1 also causes a reset signal R to be applied to G4 and the time scale is restored to $c1.1$ and $c2.1$ energised. The operation is illustrated in 1, Fig. 7.

The PM pulse which follows the PT pulse will open G20 (Fig. 4) and $f5.1$ will be energised; since M1 is a "1," $f3.1$ will be energised at this time and $f4.1$ has been prepared by the PT pulse. The operation of $f4.1$ also closes G34—G36 (Fig. 5) but opens G37 with the aid of the PM pulses (G38 and G39 remain closed due to the lack of other required controls), so that at time $t2$, G45 opens causing $f9.2$ to be energised and "0" will be recorded for M1. At time $t3$ in the PM pulse, G19 (Fig. 4) opens and $f4.2$ is re-energised.

When the waveform WM coincident with the first code section appears, both G40 and G41 (Fig. 5) are closed since $f5.2$ is no longer operative. However, G42 and G43 are partially prepared by WM and $f5.1$. At time $t2$ coincident with the first element in CH1 (Fig. 7), $r1.5.1$ (Fig. 3) will be positive so that G42 (Fig. 5) and G44 open and $f9.1$ will operate causing "1," i.e. a space, to be recorded for the first element. At time $t3$, G14 and G15 (Fig. 3) open and the pattern in R1 will be stepped one position to the right so that now $r1.5$ will record the second variable element and, since this is a mark, $r1.5.0$ and not $r1.5.1$ is positive. Thus for the second element, read at time $t2$, G43 and G45 (Fig. 5) will open and $f9.2$ will be energised causing "0" to be recorded. Again the pattern in R1 is stepped via G14 and G15; the process is repeated for the following variable elements so that F9 will have recorded the original contents of R1. The last step causes the register to be cleared with no positions energised.

For the PM pulse coincident with M2, $f3.1$ is not energised so that G34 (Fig. 5) will remain closed. G35 remains closed under control of $f5.2$ which is still non-energised but G36 is opened by $f4.2$ and $f5.1$. At time $t2$, G44 opens, $f9.1$ is energised and a "1" is recorded for the M2 element. At time $t3$ during this PM pulse, G21 and hence G22 (Fig. 4) will open and $f5.2$ will be re-energised. In consequence, the existing elements in CH2 (Fig. 7) on the drum track will be recorded as read by $f3.1$ using G40 and G41 (Fig. 5), although at this time this is of no consequence for these elements will have been left over from the previous recording. G35 causes M3 to be recorded as "0" and CH3 (Fig. 7) is reproduced by means of G40 and G41. The state of the recording is now as shown in Fig. 7(b). It should be understood that the transfer of the first character takes place in the stop period (i.e. 30 msec.) and no further

character will be passing from the teleprinter T/P to F1 at this time.

The second character is now sent from the teleprinter and, as for the first character, is passed by means of the time scale into the register R1. Whilst this is taking place the recording of Fig. 7(b) will be read by F3 (Fig. 4) and re-recorded by F9 (Fig. 5) exactly as read. Again when the time scale reaches $c2.7$, denoting that the variable elements have been received, G18 opens with pulse PT and $f4.1$ (Fig. 4) is energised. Since M1 is now a "0," the first PM pulse after this does not open G20. However, M2 is now a "1," so that the PM pulse coinciding with M2 opens G20 and $f5.1$ is energised. (See 2, Fig. 7.) This causes the contents of R1, i.e. MSMSM, to be recorded by F9 in the element positions in CH2. Also because $f4.2$ is not re-energised until time $t3$ of the PM pulse coinciding with M2, both M1 and M2 will be recorded as "0" by means of G37 (Fig. 5). Until time $t3$ of the PM pulse coinciding with M3, $f5.1$ remains energised so that a "1" is recorded for element M3 by means of G36. The elements in CH3 will be recorded by F9 as read by F3. The recording is now as shown in Fig. 7(c), and remains the same until the next and last character is transferred.

The last character is now passed as previously described from the teleprinter into the register. Again when the stop element is reached (see 3, Fig. 7) $f4.1$ is energised. The first "1" coinciding with a PM pulse occurs for M3. The elements prior to M3 will be recorded as read by means of G37 (Fig. 5) for M1 and M2 and by means of G40 and G41 for CH1 and CH2. For M3, $f4.1$ will be energised and, in consequence, M3 will be recorded as "0" by means of G37. Also the PM pulse opens G20 (Fig. 4) and causes $f5.1$ to be energised. At time $t3$ of the M3 element, G19 opens and $f4.2$ is re-energised. The fact that $f5.1$ is energised during the CH3 element positions causes the contents of R1 (Fig. 3), i.e. SSMSS, to be recorded by F9. Since there are no further M_n elements, a pulse PT coinciding with element T is used to reset F5 to the state with $F5.2$ energised. The recording is now as shown in Fig. 7(d) and for further cycles of the drum, this record will be read by F3 and re-recorded by F9.

The operator having completely recorded the message can now, or at any time later, operate key KRO to transmit the message stored. In consequence, since positive potential is removed from NX and applied to X the first PT pulse to occur after the key operation (see 5, Fig. 8) no longer opens G33 (Fig. 5) but instead opens G32 and energises $f9.1$ causing a "1" to be recorded in element T position. The remainder of the recording is made as read as shown in Fig. 8(e). The object is now to transfer the contents of CH1 into R1 so that the first character can be retransmitted. In the next cycle, when element T is read, $f3.1$ will be energised and G23 (Fig. 4) will open and cause $f6.1$ to be energised. (See 6, Fig. 8.) For the next PM pulse, i.e. coincident with M1, G34 and G35 will remain closed. Instead G38 is opened and $f9.1$ is energised causing a "1" to be recorded for M1. Also at time $t2$, PM, G28 (Fig. 4) is opened and $f7.1$ is energised and at time $t3$, PM, G24 is opened and $f6.2$ re-energised. When the WM waveform associated with CH1 appears, at time $t2$, because both $f7.1$ and $f3.1$ are energised for the first element, G16 (Fig. 3) is opened and $r1.0$ is energised. At time $t3$ of the same element G17 and G15 open and, in consequence, the contents of R1.0 are passed to R1.1. For the second element $f3.2$ is energised so that G16 remains closed but G17 again opens and causes the pattern so far set up in R1 to be moved one position to the right. Eventually the 5 elements of CH1 will have been read via G16 into R1 and stepped via G17 so that the elements will be recorded, in order of appearance, in R1.5—R1.1. Since the first character is SMSMS, $r1.5$, $r1.3$ and $r1.1$ will be energised but $r1.4$ and $r1.2$ will be non-energised. As shown in

Fig. 8(f) the elements are recorded as read, the only variation between (f) and (e) being in respect of M1 which has now become "1".

When the PM pulse coinciding with M2 appears G29 (Fig. 4) is opened at time t_1 and f7.2 is re-energised. At the same time, G5 and G6 (Fig. 2) are opened, and f2.1 is energised. This opens G1, and G2 allows $-p$ pulses to pass and the time scale begins to step.

At c1.2, G46 opens since G47 is already open to c2.1, so that f10.1 is energised. Relay TR operates, and tr1 changes over to its "s" or "space" side, and a start signal is sent to line.

At successive times c2.2, c2.3, c2.4, c2.5 and c2.6, G50 and G52 will both open, and one or other of G51 and G53 will be opened depending on the signal then coming from R1.5. For the first intelligence element of the first character, which is space r1.5.1 is positive and therefore G51 opens, followed by G47, and G46 at c1.2. f10.1 continues to be energised, and space continues to be transmitted to line. At c1.7, G55 and G15 (both in Fig. 3) open (G54 being open to c2.2) and R1 will be stepped to the right causing R1.5 to become "mark" now, for the second element of the first character, and r1.5.0 to become positive. Consequently at c2.3, G53 opens, followed by G48, and G49 at c1.2. F10 charges over to f10.2, and TR contacts return to normal, causing a "mark" to be sent.

Again at c1.7, G55 and G15 open to advance the register, so that R1.5 will contain the third element, a space, of the first character, r1.5.1 is energised, and TR returns to space at c1.2.

In similar manner, the remaining elements are transmitted to line by means of the appropriate gates, the operations of F10, the operations of TR, and the stepping of R1.

When c2.7 is reached, and at time c1.2, G48 and G49 (Fig. 6), open, f10.2 is energised and tr1 return to normal to send a final "mark" signal to line, as the "stop" signal. This persists till the time c1.7, c2.8, i.e. 150 msecs. from the commencement of the signal, when G7 (Fig. 2) opens, and f2.2 is re-energised, stopping the time scale and generating the reset pulse T. This pulse opens G4 and the time-scale is reset with positions c1.1, c2.1 energised.

As shown in 7, Fig. 8, whilst the first character is being transmitted, no further transfer from the drum into the register can take place. f2.2 non-energised prevents G23 (Fig. 4) opening and f6.2 remains energised. The contents of the memory will be recorded by F9 as read by F3, as indicated by Fig. 8(g) which is the same as Fig. 8(f).

When f2.2 is re-energised, the first PT pulse which follows opens G23 and f6.1 is energised as shown in 8, Fig. 8. Because M1 is now "1," F3 is at f3.1 and G28 is not opened by the PM pulse coinciding with M1. Instead it opens for the PM pulse coinciding with M2, which is read as "0," F3 going to f3.2. The elements in CH1 are recorded as read by F3, under control of G40 and G41. At time t_2 , PM, of the M2 element, G28 opens and f7.1 is energised. The elements in CH2 now pass via G16 (Fig. 3) into R1.0 and are stepped along under control of G17. The record is now as in Fig. 8(h) which differs from (g) in respect of the M2 element only. f7.2 (Fig. 4) is re-energised via G29 for the PM pulse coinciding with M3. At the same time G5 (Fig. 2) opens, f2.1 is energised and the time scale started. F10 (Fig. 6) causes the contents of R1, which denote the second character, to be transmitted to line together with the necessary start and stop elements.

Nothing further occurs until this character is fully transmitted, the recording being made as read. When the time scale is stopped by G7 opening when the necessary $7\frac{1}{2}$ uniperiods have elapsed, f2.2 being re-energised allows the next PT pulse to open G23 (Fig. 4) and f6.1 is energised. (See 9, Fig. 8.) The fact that f3.2 is energised for M3, and not for M1 and M2, causes G28 to open and f7.1 to be energised at a time t_3 , PM coin-

ciding with M3. f6.1, which remains energised until this time, causes M1, M2 and M3 to be recorded as "1" by means of G38. f7.1 allows the contents of CH3 to pass to R1 in the manner already described. Since this is the last character, there are no further PM pulses in this section and f2.1 (Fig. 2) is energised via G8 and G6. The third, and last character, as stored in R1, is now transmitted to line by means of F10. The recording is now as shown in Fig. 8(i).

When the last character has been transmitted, and f2.2 re-energised, f6.1 will again be energised by the PT pulse (see 10, Fig. 8) but now that M1, M2 and M3 are all "1," G28 cannot open. f6.1 causes these elements to be re-recorded as "1." F6 is returned to f6.2 energised by means of G27, which operates with the last pulse of the section, PL. Element T is recorded as "1" by means of G32 and the contents of CH1, CH2 and CH3 are recorded by means of G40 and G41 and the recording remains as shown in Fig. 8(i).

After the message has been sent, it is possible to return to the initial state by automatic means but this would entail the use of an auxiliary head and attendant equipment to change the state of element T back to "0." For convenience it has been assumed that to return to the initial state, the operator restores KRO. When KRO is restored (see 11, Fig. 8), the next PT pulse opens G33 (Fig. 5) and f9.2 is energised causing a "0" to be recorded for element T. Also the PT pulse opens G23 (Fig. 4) causing f6.1 to be energised as in previous cycles but this time G31 opens also, because T was previously a "1" and f3.1 will be energised, and, in consequence, f8.1 is energised. Thus in the subsequent PM pulse, a time f3, G26 is opened and f6.2 re-energised. However, since f6.1 is still energised at t_2 of this pulse, a "1" is recorded via G38 (Fig. 5) for element M1. For the following PM pulses, f6.2 will be energised and G39 opens, and not G34, and M2 and M3 are recorded as "0." The recording is now as shown in Fig. 8(j), and is the same as the initial recording. Until a further message is sent from the teleprinter this record will be recorded by F9 as read, under control of the respective gates and the control equipment will remain in the initial state.

As shown in the diagram, when retransmission is taking place, a new character is not transferred from the drum into R1 until the previous character, including stop elements, has been transmitted. This represents a small wastage of time but this wastage could be removed by modifying the arrangement so that a new character could be transferred during the stop period of the character then being transmitted.

The system has been described for one teleprinter termination and one recording section. However, by means of a multiplex arrangement, such as described in our above mentioned copending applications more than one message could be stored on one track. This has not been described here to avoid unnecessary complication. For such a system Figs. 2, 3 and 6 would be individual to the terminating circuits but Figs. 4 and 5 would be common to all message sections on one track. The connections between the individual terminations and the common circuit, e.g. r1.5.1 and f4.2 would be multiplexed.

As described, a fixed message length has been assumed but simple modifications would make it possible to have a varying length of message. For instance, a special end of message character could be used; detection of this character would be used to cause the T element to be made 1. Similarly, when reading out, detection of the end of message characters would be used to cause T to become 0 again and the recording returned to the initial state.

Further, the system has been described as applied to one track on a drum. A drum may, however, readily accommodate up to 200 tracks side by side, with their reading and recording heads staggered if necessary

around the periphery so that not more than, say, 20 must be accommodated side by side axially along the drum. A single clock track on the drum can then control the operations for recording and reading for the whole 200 tracks so that messages from various destinations may be stored simultaneously (or contemporaneously) on several tracks while messages already stored are being retransmitted from other tracks.

It is, moreover, pointed out that the operations for recording (or reading) and advancing the register, which involve the M1, M2 etc. pulses, are effected with the one head. That is to say, that the "work" head is also utilised for making the identifying transitions from 1 to 0, or for detecting the transitions from 0 to 1, as the case may be, for determining when recording (or reading) may begin.

A further alternative, not at present regarded as a preferred arrangement, is to effect the transfer from register to store element by element instead of character by character (a character being, in the example described, a collection of five elements). For this, R1 in Fig. 3 would be a simple bi-stable device, which is effectively a 2-position register, and the drum speed would need to be arranged so that the rotation time was less than an elemental period (in the example 20 milliseconds).

Equally to go in the other direction, each individual store, i.e. between "M" markings, could be arranged to accommodate more than one character with suitable rearrangement of the controls.

While the principles of the invention have been described above in connection with specific embodiments, and particular modifications thereof, it is to be clearly understood that this description is made only by way of example and not as a limitation on the scope of the invention.

What we claim is:

1. Equipment for the storage and re-transmission of a plurality of items of intelligence consisting of coded electrical signals, comprising an incoming receiving channel, an outgoing transmitting channel, a record member containing a plurality of recording tracks each including a plurality of electrical signal stores, receiving means for receiving items of intelligence over said incoming channel and applying them successively to predetermined ones of said stores, means associated with said stores for deriving a plurality of control pulses, transferring means for applying predetermined ones of said pulses successively to different ones of said stores as to set up thereby distributor signal marks in said stores to mark the order of the successive predetermined use of said stores as repositories of said intelligence, and means for successively transmitting over said outgoing line in the order as recorded stored items of intelligence previously recorded in said stores.

2. Equipment as claimed in claim 1 wherein said receiving means include means for the reception of constant total permutation code characters of n elements, one character per store, and which comprises a temporary store arranged to store a single character, means for completely receiving the elements of each character on receipt in the said temporary store, and means for completely transferring a temporarily stored character into the next one of said plurality of stores to be used.

3. Equipment as claimed in claim 1 wherein said receiving means includes means for the transmission of constant total permutation code characters of n elements, stored one character per store, and which comprises a temporary store arranged to store a single character, means for completely transferring the elements of a character to be transmitted to said temporary store under control of said marking means, and means to transfer said temporarily stored character to a permutation code signal transmitter.

4. Equipment as claimed in claim 2 and in which said

temporary store comprises a pattern movement register of known type.

5. Equipment for the reception, storage and subsequent re-transmission of constant total permutation code characters comprising a start element, n variable elements, and a stop element, which comprises an incoming line, an outgoing line, a track on a magnetic drum constituting a plurality of storage sections, recording and reading means for said track, a temporary store comprising a pattern movement register, means for receiving from said incoming line all the variable elements of a complete character in said register, distributing means for applying a mark to said track for indicating the next section thereof to be used for storage, means for detecting such mark, means under control of said detecting means and the stop element of the character in said temporary store to cause the transfer of the contents of said temporary store into said marked storage section, means to cancel a detected mark on transfer and to insert a new mark at the end of transfer at the beginning of the next track storage section; means to initiate transmission of stored characters from said storage sections, including means to detect an identifying mark in the storage section containing the first character stored, means to transfer to said temporary store the first character stored in a storage section, means to transmit with stop and start elements a character stored in said temporary store to said outgoing line, means to transfer thereafter in turn to said temporary store character stored in subsequent sections of said track, and means to transfer said identifying mark from storage section to storage section as each storage section on said track is emptied.

6. Equipment for the sequential storage of a plurality of items of intelligence consisting of coded electrical signals, comprising a record member containing a plurality of recording tracks each including a plurality of electrical signal stores, means for applying a distributor signal mark to a first store which is in a condition to receive and store a first item of intelligence, distributor mark transferring means responsive to said first store being taken into use for cancelling the distributor mark signal from said first store and applying a distributor mark signal to a second store, detecting means for sequentially examining said stores for the presence of a distributor signal mark and means responsive to said detecting means for successively directing said first and a second item of intelligence, respectively to said first and second stores in the order named.

7. Equipment for the storage and subsequent retransmission of a plurality of items of intelligence consisting of coded electrical signals, comprising a record member containing a plurality of recording tracks each including a plurality of electrical signal stores, means for recording said items of intelligence successively in said stores, means for applying a distributor signal mark to a first store containing the first item of intelligence to be transmitted, distributor mark transferring means responsive to said first store being emptied for cancelling the distributor mark signal from said first store and applying a distributor mark signal to the store in which said second item of intelligence is stored, detecting means for sequentially examining said stores for the presence of a distributor signal mark, and means responsive to said detecting means for successively extracting said first and second items of intelligence from said first and second stores, respectively, in the order named.
